LIFT TRUCK

Arthur M. Barrett, Winnetka, Ill., assignor to Barrett-Cravens Company, Chicago, Ill., a corporation of Illinois

Application July 6, 1936, Serial No. 89,036

15 Claims. (Cl. 254—10)

The present invention contemplates certain improvements in construction and operation of lift trucks of the general type employing a wheeled lower frame supporting an upper frame 5 adapted to be raised and lowered with respect thereto, the upper frame being movable, in lowered position, under platforms or the like, and being then raised to support the platform for transportation by the truck.

10 In the main, the present invention is directed to certain improvements in the means for raising the upper platform and holding the same in raised position, and in the means for controlling the lowering of the platform when it is desired to 15 discharge the load.

One object of the present invention is the provision of improved lifting means including a ratchet and pawl connection, whereby oscillation of the steering handle results in imparting 20 a jacking or lifting force to the upper frame to raise the same into its upper position. In this connection, I have provided improved means for connecting the operating crank with the steering handle, in order that the cranking movement may 25 be produced with the steering handle in any steering position. In addition, I have provided an improved ball and socket connection between the ratchet and pawl carriage mechanism and the upper frame, so that the angularity introduced in the ratchet shaft due to the forward and upward movement of the frame will not produce binding or shackling of the lifting mechanism.

Another advantage of the present invention is 35 the provision of such swiveling connection whereby the oscillation of the handle results in reciprocating movement of a ratchet with respect to a pawl normally pressed into engagement therewith, so that regardless of the angularity of the 40 oscillating handle, the same straight line reciprocating force will be imparted to the ratchet shaft.

Another feature of the present invention is the provision of release means for accommodating 45 lowering of the platform supporting frame. This essentially comprises a mechanism operated preferably by the foot of the operator, which first disengages the ratchet and pawl connection, and then, while maintaining this ratchet and pawl 50 connection disengaged, operates to release the holding check which normally supports the platform in raised position. In disengaging the ratchet and pawl connection, I preferably provide a camming member which moves the pawl 55 into inoperative position, and which is so con-

structed that as the pawl moves angularly due to the fact that it is supported on the upper frame, the cam surface will maintain it in inoperative position as long as the releasing mechanism is energized. Also, I preferably provide a 5 mechanism such that during the first part of its operating movement, which releases the pawl and ratchet engagement, no release of the holding or locking means is effected, whereby it is assured that the ratchet and pawl connection 10 will be released prior to release of the holding mechanism.

Another feature of the present invention of distinct advantage is the provision of a separate foot operated member for effecting disengagement of the pawl from the ratchet shaft without 15 in any manner affecting the holding effect of the locking means. This is of distinct advantage in situations where the operator lifts the upper frame with only two or three strokes of the steering handle, and finds that no further lifting force is required in order to transport the load. However, inasmuch as the draft handle, which is used for pulling the load, is also oscillatable to lift the frame, every time any motion of the handle is 20 made the ratchet will be actuated. It is of distinct advantage to have the ratchet and pawl connection disengaged during the transportation of the load by the truck, and for this purpose a 25 separate means is provided for actuating the camming member to disengage the pawl while not in any manner affecting the support of the load by the holding check means.

Still another feature of the present invention is the provision of a novel type of hydraulic check 35 for holding the upper frame in any raised position, and for preventing its lowering except after disengagement of the ratchet and pawl connection which effects raising of the frame. It is particularly advantageous, in the present construction, to provide such a hydraulic check 40 which is so connected to react between the upper and lower frames that the angular lifting movement of the upper frame does not produce any binding or shackling action, but the hydraulic check is so mounted that it is swiveled in accordance with this movement into the desired position.

Another distinct advantage secured by the 50 present check construction is the provision of a control valve mechanism whereby a metered control of the lowering of the platform is effected, so that the platform can be lowered at any desired rate. This insures safety to the operator, 55

and prevents undue stressing of the supporting frame or of the mechanism.

Other objects and advantages of the present invention will appear more fully from the following detailed description, which, taken in conjunction with the accompanying drawings, will disclose to those skilled in the art the particular construction and operation of a preferred form of the present invention.

10 In the drawings:

Figure 1 is a side elevational view of a lift truck embodying the features of the present invention;

Figure 2 is a top plan view showing details of the modified construction;

15 Figure 3 is a more or less diagrammatic view of the raising and releasing means in one of its operating positions;

20 Figure 4 is an enlarged view of the mechanism shown in Figure 3, illustrated in a slightly different operating position;

Figure 5 is a side elevational view, partly in section, of the hydraulic check mechanism for locking the lifting frame in its raised position; and

25 Figure 6 is a sectional view through the control valve of the mechanism shown in Figure 5.

Referring now in detail to the drawings, in Figures 1 and 2 I have disclosed in general the arrangement of the constituent parts of the present invention with respect to a lift truck of more or less conventional design. The lift truck essentially comprises a lower supporting frame 5, having at its rear end suitable journals for supporting a rear axle shaft 6 upon which are mounted the rear supporting wheels 7. Secured to the axle 6 30 is a suitable crank member 8, having bearing engagement within the angle member 9 extending transversely across the upper or lifting frame, indicated generally at 10, and comprising the side members 12 extending substantially parallel to the side members 13 of the lower frame. At the forward end, the side members 13 of the lower frame 5 are adapted to provide pivotal support as indicated at 14, for link members 15 connected to the forward end of the side members 12 of the upper or lifting frame 10. A suitable crosshead 16, 35 which constitutes a part of the lower frame structure, extends between the forward ends of the side frame members 13 and provides a pedestal mounting for a shaft extending through the bearing plate 18 and having a yoke at the lower end upon which is pivotally mounted the steering wheel 19.

The bearing plate 18 is provided with an upwardly extending portion 20 terminating in spaced arms 22 forming a pivotal support for a pin 23 upon which is mounted the operating handle and steering handle 24. This handle is mounted for pivotal movement about the pin 23 to be oscillated in a generally fore and aft direction. However, the handle 24 is also adapted to 40 swing the supporting bracket 20 and bearing plate 18 in a pivotal direction about the pedestal 16 in order to effect steering movement of the wheel 19.

The arms 22 also provide means therebetween, supported on the pivot 23, for the pivotal mounting of the crank 25, which crank is provided at its upper end with a lip portion 26 engaged by the lip portion 27 of the hook member 28 pivotally mounted, as indicated at 29, on the handle 24. The hook member 28 locks the crank 25 for joint oscillating movement with the handle 24, but is releasable when it is desired to lower the handle 24 for draft purposes.

The opposite end of the crank 25 is provided with a cup-shaped end portion 30, forming a ball and socket joint with the ball member 32 disposed

therein. A suitable bolt 33 holds the ball member in the socket 30, and at its opposite end is connected to a second ball member 34 secured in the cup or socket portion 35 of a crank 36. This provides a pivotal swiveling connection between the cranks 25 and 36, so that regardless of the angular movement of the bearing plate 20 and the steering handle 24, any vertical oscillation of the handle in any fore and aft or laterally disposed position will produce rocking movement of the crank 36 about its pivotal support 37 carried by the outer ends of the arms 38 preferably formed integral with the crosshead 16 and extending rearwardly and upwardly therefrom.

The opposite end of the crank 36, as more clearly shown in Figures 3 and 4, is provided with a journal portion 39, forming a support for the pivot pin 40 which secures the end of the ratchet shaft 42 for pivotal connection with the portion 39 of the crank 36. The ratchet shaft 42 is provided with the ratchet surface 43 along one edge thereof, and the free end of the ratchet shaft 42 is adapted to extend through the pawl carriage 44 which has the extending arms 45 forming supporting means for the pivot pin 46 upon which the pawl 47 is pivotally mounted. The projecting end of the pawl 47 is provided with a camming offset 48, which is engaged by one end of the spring member 49 carried by the pin 46, and normally is urged in a counterclockwise direction to force the toothed end 50 of the pawl into engagement with the ratchet surface 43 of the ratchet shaft 42. The pawl carriage 44 is mounted for swiveling movement with respect to the platform or lifting frame 10, this frame being provided with the angle member 52 extending transversely thereacross at the forward end thereof to form a load or platform stop, and being provided with the reinforcing structural members 53 welded to the under surface thereof and carrying the casting 54 having transversely spaced socket portions 55 formed therein. The pawl carriage 44 has corresponding ball members 56 formed integral therewith, which are engaged in the socket portion 55 of the casting 54, so that the pawl carriage 44 is swivelly connected by the double ball and socket connection to the upper lifting frame through the structural member 53 and the platform stop 52.

This is of distinct advantage in that as the lifting frame is moved upwardly and forwardly into raised position, the angularity of the ratchet shaft 42 with respect thereto changes, since the outer end of the ratchet shaft 42 is mounted on a pivot located by means of the arms 38 and the corresponding pivot 37 of the crank 36. Without such a swivelling connection, binding or shackling of the ratchet shaft with respect to the pawl carriage might be occasioned.

In the operation of the structure thus far described, when the handle 24 is oscillated in a fore and aft direction, regardless of its angular steering position, it imparts a corresponding rocking movement to the crank 36 through the crank 25. This results in a reciprocatory movement of the journal portion 39 of the crank 36, resulting in reciprocation of the ratchet shaft 42 with respect to the pawl carriage 44. As a result, the ratchet 43 is first reciprocated axially downwardly through the carriage 44 ratcheting past the pawl 47 and is then moved upwardly with respect thereto. Its upward movement results in locking engagement with the toothed portion 50 of the pawl 47, thereby exerting a lifting force on the upper frame 10, and due to the link connection of

this frame through the members 8 and 15, results in a forward and upward movement about the pivots 14 and 6 as centers.

Considering now Figures 1 and 2 in connection with Figure 5, the lower frame 5 has, extended transversely between the side members 13 thereof, the supporting member 60 which comprises a fabricated structure of substantially right angular shape, as shown in detail in Figure 2. This member 60 is disposed at a slight angle with respect to the horizontal plane of the frame 5, and is provided at the forward surface of its vertically extending portion with a ball member 62 adapted to engage in a spherically shaped recess 63 formed in a supporting plate 64 carried by the rear end of a hydraulic check cylinder indicated generally at 65. The cylinder itself comprises the cylindrical portion 65 and the enlarged reservoir portion 66 at the forward end thereof. The rear end of the cylinder portion 65 is provided with outwardly extending flanged portions 67 carrying bolts 68 adapted to extend through the vertical portion of the bracket 60 and to have resilient mounting in enlarged openings therein, as indicated generally at 69.

Disposed within the cylinder 65 is the piston member 70, having the coaxially extending piston rod 72 projecting outwardly through the packing gland member, indicated generally at 73. The outer projecting end of the piston rod 72 is provided with suitable ball and socket locking engagement, as indicated at 74, in a downwardly extending flange 75 forming a part of the fabricated structure 53 disposed beneath the platform stop 52.

The reservoir portion 66 of the hydraulic check means is provided with an inlet opening suitably closed by the closure cap 76, and also provided with a screen 77 for filtering the liquid, such as oil or the like, which fills the interior of the reservoir 66.

In the operation of the hydraulic check, as the upper frame moves upwardly and forwardly, the platform stop 52 and the flange 75 have corresponding upward and forward movement. As a result, due to the swivelling connection 74, the piston rod 72 is moved axially outwardly of the cylinder 65, moving the piston 70 to the left, as viewed in Figure 2. This results in pressure being applied to the liquid at the left hand side of the piston 70, and this liquid is bypassed through the piston by means of the ball check valve 78, the passageway 79, and the second ball check valve 80, to the rear or trailing side of the piston 70. The ball check valves 78 and 80 are normally spring-pressed into closed position, but open upon movement of the piston to the left to provide communication between the interior chamber 82 of the cylinder 65 at the left hand side of the piston 70 and the cylinder at the right hand side of the piston 70. As a result of this displacement of liquid through the piston, the piston moves with the upper frame, and the entire cylinder 65 swivels about the ball and socket connection 62, 63 to assume an angular position determined by the forward and upward movement of the lifting frame 10.

It will be apparent that due to the fact that liquid fills the cylinder at the right hand side of the piston as the piston moves to the left, any reverse movement of the piston 70 is prevented, and thus the frame 10 is held in any position to which it may be raised by oscillation of the handle 24.

In order to provide for lowering of the frame 10

when it is desired to dispose of the load, a control valve indicated generally at 90 is provided. This control valve, as indicated in detail in Figure 6, comprises a shaft element 91 which has a reduced threaded portion 92 threaded internally of the valve cage member 93, which cage member in turn is threaded at 94 into a laterally extending offset 95 of the cylinder 65. The shaft 90, at its inner end, is provided with the tapered valve portion 96 adapted to have seating engagement with the valve seat 97 formed in the valve cage member. The reduced portion of the shaft 90 between the valve portion 96 and the threaded portion 92 is of smaller diameter than the passageway 98 extending through the valve cage member, and as a consequence when the shaft 90 is unthreaded to unseat the portion 96 from the valve seat 97, fluid within the cylinder 82 can pass outwardly through the passageway 98 and the normally extending passageway 99 into the annular opening 100 disposed about the valve cage member and communicating through the side passageway 102 with the main reservoir chamber 66. The shaft 90 is sealed against leakage by means of the packing 103 retained in sealing engagement with the lateral surface thereof by the spring 104, while the valve cage member 93 is sealed by the packing 105 disposed in an enlarged annular recess thereof and compressed into position by the spring 106.

The outer projecting end of the shaft 90 is clamped between opposite arms of a suitable cranking member 107, which crank member is provided with an offset projecting pin 108 adapted to be engaged by the end 109 of a control lever 110. Suitable stop means 112 is provided to prevent the forked end 109 of the lever 110 from slipping laterally off of the pin 108.

At its opposite end, the control lever member 110 is pivotally mounted, as indicated at 113, upon the lever 114 pivotally mounted at its lower end on the pin 115 carried by a forwardly extending ear 116 of the cross head 16.

The upper end of the lever 114 carries a pivot pin 117 which establishes pivotal connection with the lower or forward end of a link 119. The lever 114 and link 119 constitute the two parts of a toggle linkage, of which the pivot 117 is the knuckle joint. Forward and rearward throw is imparted to this knuckle joint 117 by an actuating link 118 which has its rear end connected with said knuckle pin. The actuating link 118 at its opposite end, is connected through the pivot pin 120 with the lower end 122 of a treadle member 123 mounted for independent rotation upon the shaft 124 extending transversely across the cross-head 16 and supported at the inner ends of the extending arms 38. On the upper side of the shaft 124 and formed as a part of the member 123 is a rearwardly extending substantially horizontal treadle portion 125, adapted for actuating the member 123 to rotate the same about the shaft 124, and also formed as a part of the member 123 a return treadle portion 126 adapted to be engaged by the operator for returning the mechanism to normal position.

Mounted on the shaft 124 inwardly of the treadle member 123 is a camming member indicated generally at 130, which is keyed to the shaft for conjoint rotation therewith, and which has camming surface 132 formed thereon and adapted to engage the offset cam roller 48 of the pawl member 47.

Intermediate its ends, the member 130 is provided with a journal portion supporting a pivot 75

pin 133 to which is pivoted the upper end of the upper toggle link 119.

The shaft 124, which extends transversely across the crosshead 16 and is supported for rotation in the lower and inner ends of the arms 38, has mounted on its opposite end the hub portion 135 of a second auxiliary treadle member 136, the treadle member 136 being secured rigidly to the shaft 124 whereby upon actuation thereof the shaft is rotated. When the treadle member 136 is moved downwardly, the shaft 124 rotates in a counterclockwise direction, and thus produces counterclockwise rotation of the member 130. This moves the camming surface 132 of the member 130 upwardly into engagement with the roller 48, moving the pawl 47 in a clockwise direction out of engagement with the ratchet shaft 42. As a result, the ratchet shaft is disengaged, and the shaft and carriage are free to have relative movement. However, it must be understood that even with disengagement of the pawl 47, the upper lifting frame will be maintained in position due to the holding check provided by the hydraulic piston and cylinder arrangement previously described.

It sometimes happens that an operator finds that he can lift the load upon the lifting frame 18 with only one or two strokes of the handle 24, and consequently does not impart full lifting movement to the frame 10. As a result, any further oscillation of the handle 24 during hauling of the truck may result in further raising movement of the lifting frame, which is undesirable. In order to prevent such an occurrence, the operator need merely depress the treadle member 136, thereby rotating the shaft 124 and disengaging the pawl 47 from the ratchet shaft 42. As a result, further oscillation of the handle 24 will not result in imparting any further lifting movement to the lifting frame 10, since the ratchet and pawl connection has been disengaged. The operator may therefore safely oscillate the handle during pulling of the truck to the desired position, and may then actuate the mechanism controlled by the treadle member 123 to secure release of the hydraulic holding means for lowering the lifting frame.

The oscillation of the mechanism shown in details in Figures 1, 3 and 4, which controls the lowering of the lifting frame, is adapted to produce two separate and distinct results during its movement through its operating range of position. Briefly, when the treadle member 125 is depressed, it produces counterclockwise rotation of this member about the shaft 124. This results in angular movement of the end 122 of the treadle member, producing a thrust through actuating link 118 upon the knuckle pivot 117 of the toggle links 114 and 119, and thereby producing a lifting effort on the member 130 to raise the cam surface 132 thereof into engagement with the roller 48 to disengage the pawl 47 from the ratchet shaft 42. This occurs immediately upon initial depression of the treadle member 125. However, during this first part of the downward movement of the treadle 125 the resultant motion of the toggle linkage is practically the same as that effected by the complete depression of the other treadle 136. Thus, during approximately one-half of the downward movement of the treadle member, no substantial movement of the check controlling link 110 is accomplished, and disengagement of the pawl is assured prior to any actuation of the release means for the hydraulic check.

As the pivot 117 between the toggle members 114 and 119 passes through and beyond the dead center relation of the pivots 115 and 133, a substantial clockwise rotative movement is imparted to the toggle lever 114. This in turn produces a thrust upon the left hand end of the control link 110, causing it to move to the right and to rotate the crank 107 in a counterclockwise direction. Rotation of the crank in this direction unthreads the valve member 98 from the valve seat 97, resulting in release of the liquid compressed on the right hand side of the piston 78, allowing the piston to return to its normal position and lowering the frame 10. While the hydraulic holding means is constructed to lower the load at a relatively slow, safe speed, the operator is also enabled to reduce the lowering speed or to stop and start the lowering, if desired, by alternately depressing the treadle members 126 and 125.

It is therefore believed apparent that I have provided a lift truck design in which the upper frame can be raised into load supporting position independently of the angle at which the steering handle is disposed, and that oscillation of the steering handle about its horizontal pivot will result in jacking of the frame into raised position due to the pulling connection between the cranks. Also, it is apparent that by the provision of the hydraulic check which is expanded upon movement from the frame, the upper frame can be maintained in any raised position automatically, without the setting of any holding up means by the operator.

By the provision of the improved control mechanism for controlling the lowering of the frame, it is possible to use the steering handle for draft purposes without effecting the position of the upper frame, and it is also possible to disengage the pawl and ratchet connection independently of actuation of the check. It is obvious that the check must be held locked in position at all times that the ratchet and pawl connection is maintained, since otherwise the load on the upper frame would probably result in undue stressing of the ratchet and pawl connection. Thus, the particular mechanism is peculiarly adapted for effecting the proper sequence of operation in lowering of the frame without any skilled operation on the part of the operator.

I am aware that various changes both in design and construction of various constituent parts of the present invention can be made without in any manner altering the underlying principles of the present invention, and I therefore do not intend to be limited to the exact features shown and described, but only in so far as defined by the scope and spirit of the appended claims.

I claim:

1. In a lift truck of the class described having a lower frame including, a cross head at one end thereof, an upper frame, means connecting said frames for upward and forward movement of said upper frame with respect to said lower frame, a steering handle pivotally carried on the cross head, ratchet and pawl means controlled by oscillation of said handle for lifting said upper frame into raised position above said lower frame, hydraulic check means for holding said upper frame in raised position, and toggle actuated release means operable during the initial part of its movement to release said pawl means from said ratchet and subsequently operable to release said hydraulic check means while maintaining said pawl in released position.

2. In combination, a lift truck having a lower

frame including a cross head and an upper frame, an operating and steering handle swivelly mounted on said cross head for steering movement and pivotally mounted on a horizontal axis for operative movement, a pawl and ratchet connection between said handle and said upper frame including means providing a swivelling engagement between said handle and said connection whereby oscillation of said handle about said horizontal axis in any steering position raises said upper frame with respect to said lower frame, hydraulic means automatically locking said upper frame in fixed position at any point in its raising movement, and toggle actuated release means for lowering said upper frame comprising means for initially disengaging said pawl and ratchet connection and subsequently releasing said hydraulic locking means while maintaining said pawl and ratchet connection disengaged.

20 3. In combination, a lift truck comprising a lower frame, an upper frame, means for raising said upper frame with respect to said lower frame comprising a reciprocable ratchet bar and a cooperating pawl pivotally mounted on said upper frame, independent means operable during said raising movement for holding said upper frame fixed in any raised position, and treadle means operable in one direction for first pivotally swinging said pawl out of engagement with said ratchet bar and subsequently releasing said holding means, said treadle means being operable to control the rate of lowering of said upper frame under load.

4. A lift truck comprising a lower frame mounted on rear wheels and a laterally steerable front wheel, an upper frame mounted on said lower frame for upward movement relative thereto, a steering and lifting handle pivotally mounted on said truck, raising means for said upper frame comprising a ratchet bar adapted to be reciprocated by said handle, and a pawl pivotally mounted on said upper frame and cooperating with said ratchet bar, said raising means being operable upon oscillation of said handle in any steering position for jacking said upper frame upwardly with respect to said lower frame, hydraulic means operable during said jacking to have relative separating movement between said frames and including means for locking said upper frame against lowering from any raised position, means for lowering said upper frame including means for pivotally swinging said pawl out of engagement with said ratchet bar and means for subsequently effecting restricted release of said locking means to permit lowering of said upper frame.

5. A lift truck comprising a lower frame, an upper frame adapted to be raised and lowered with respect thereto, a raising handle pivotally mounted for oscillation on said truck, a ratchet adapted to be reciprocated upon oscillation of said handle, a pawl swivelly mounted on said upper frame and operatively engaging said ratchet upon upward movement thereof whereby reciprocation of said ratchet imparts raising movement to said upper frame, means locking said upper frame in raised position independently of said raising means, and means comprising a pivoted cam member operable to pivotally swing said pawl out of engagement with said ratchet and to maintain said pawl disengaged during lowering movement of said upper frame upon release of said locking means.

6. In a lift truck having means for raising an upper frame and including independent means for locking said frame in raised position, the

combination of means for controlling lowering movement of said upper frame from raised position comprising toggle links and cooperating cam means for initially disengaging the raising means while retaining the locking means in operative position, and means operable upon further movement of said controlling means in the same direction for releasing said locking means while retaining said raising means in disengaged position.

7. In combination, a lift truck comprising a lower frame and an upper frame, a steering handle pivotally mounted on said truck, a pawl carriage having ball and socket connection with said upper frame, a pawl pivotally mounted on said carriage, a ratchet shaft pivotally supported above said lower frame, lever means connecting said shaft to said handle including a swivelling ball and socket connection whereby oscillation of said handle produces reciprocating movement of said ratchet shaft with respect to said pawl, and means on said pawl engaging said shaft upon movement in one direction thereof to raise said upper frame with respect to said lower frame.

8. In combination, a lift truck comprising an upper frame and a lower frame, said upper frame being movable vertically with respect to said lower frame, means for raising said upper frame including a pawl and ratchet connection, means for locking said frame in raised position, a treadle member pivotally supported adjacent one end of said lower frame, a pawl-engaging cam pivoted coaxially with said treadle member, a toggle connection between the extending ends of said treadle member and cam for maintaining said cam in pawl-releasing position throughout actuating movement of said pedal member, and means extending between said toggle connection and said locking means for releasing said locking means when said toggle connection passes over-center position.

9. In combination, a lift truck comprising an upper frame and a lower frame, said upper frame being movable vertically with respect to said lower frame, means for raising said upper frame including a pawl and ratchet connection, means for locking said frame in raised position, a treadle member pivotally supported adjacent one end of said lower frame, a pawl-engaging cam pivoted coaxially with said treadle member, a toggle connection between said cam and a pivot point on said lower frame and actuated by said treadle member for maintaining said cam in pawl-releasing position throughout actuating movement of said pedal member, means extending between said toggle connection and said locking means for releasing said locking means when said toggle connection passes over-center position, and a second treadle member pivotally mounted on said lower frame for moving said cam into pawl-releasing position independently of said first treadle member and said toggle connection.

10. In a lift truck having a lower supporting frame including a cross head at one end thereof and an upper frame adapted to be raised and lowered, a platform stop on said upper frame, means secured to said stop including a pair of spaced sockets, a pawl carriage having balls engaged in said sockets providing for rocking of said carriage with respect to said upper frame, a pawl pivotally supported in said carriage, a ratchet shaft adapted for reciprocating movement in said carriage and engaged by said pawl, a supporting member secured on said lower frame, an actuating crank pivotally mounted

- on said member and having pivotal connection at one end with said shaft, a ball member at the opposite end of said crank; a steering handle swivelled in said cross head and pivotally mounted 5 for oscillating movement about a horizontal axis, a crank actuated by oscillating movement of said handle, and a swivelling connection between said last-mentioned crank and said ball member of said first-mentioned crank for rocking said first-mentioned crank to reciprocate said ratchet shaft with respect to said pawl regardless of the angular steering position of said handle.
11. A lift truck having a lower frame, an upper frame, a ratchet guide having ball and socket support on said upper frame including a pivotally mounted pawl, a ratchet carried by said lower frame and adapted to be reciprocated in said guide for engagement with said pawl to raise said upper frame, hydraulic means for locking said frame in raised position, and means operable independently of said ratchet for pivoting said pawl out of engagement with said ratchet and for thereafter releasing said locking means to effect lowering of said upper frame.
12. Raising means for a lift truck having a lower frame including a cross head and an upper frame, comprising a ratchet guide pivotally supported on said upper frame adjacent said cross head, a pawl pivotally mounted in said guide, a crank means pivotally supported on said cross head and including a ratchet extending through said guide and reciprocated therein upon operation of said crank means, spring means normally pressing said pawl into engagement with said ratchet to effect raising movement of said upper frame upon alternate reciprocations of said ratchet, and separate means pivotally supported on said cross head for pivoting said pawl out of engagement with said ratchet.
13. A lift truck comprising a lower frame having a cross head and an upper frame, a steering and operating handle pivoted from a horizontal axis on said cross head and including a coaxially pivoted bell crank, a second bell crank pivotally supported on said cross head in a position offset from said first bell crank, ball and socket connection between one end of said first bell crank and one end of said second bell crank, a ratchet pivotally supported at the other end of said second bell crank, and pawl means carried by said

upper frame and engaging said ratchet whereby upon oscillation of said handle said ratchet is reciprocated in said pawl means to raise said upper frame.

14. In a lift truck of the class described, the combination of a main frame mounted on rear wheels and a laterally steerable front wheel, a lifting frame mounted on said main frame for upward movement relative thereto, an operating handle pivotally mounted on said main frame for vertical swinging movement, and also for lateral swinging movement to steer said front wheel, pawl and ratchet raising mechanism actuatable by vertical swinging movement of said handle for raising said lifting frame, hydraulic means governing said lifting frame comprising a cylinder pivotally connected with said main frame and a piston in said cylinder pivotally connected with said lifting frame, a bypass in said cylinder adapted to bypass liquid from one side of said piston to the other, a valve associated with said cylinder extending substantially at right angles thereto and operative to control said bypass, threaded means for causing axial motion of said valve upon rotation thereof, a crank on said valve for rotating the latter, a link arranged to transmit motion to said crank, and control apparatus operative to release said pawl and ratchet mechanism and also operative to impart thrusting motion to said link for actuating said valve.

15. In a lift truck of the class described, the combination of a dirigible, wheeled main frame, a lifting frame mounted on said main frame for upward movement relative thereto, an operating and steering handle pivotally mounted on said truck, pawl and ratchet raising mechanism actuated by said handle for raising said lifting frame, a holding device in the form of an extensible and contractible strut extending between said frames for holding said lifting frame in elevated position, a cam for releasing said pawl and ratchet raising mechanism, toggle links for moving said cam into operative position, a trip member for actuating said toggle links, and means responsive to the motion of said toggle links for releasing said holding device.

ARTHUR M. BARRETT.
